No. 766,244.

PATENTED AUG. 2, 1904.

F. HACHMANN.
SELF OILING BEARING.
APPLICATION FILED OCT. 5, 1903.

NO MODEL.

UNITED STATES PATENT OFFICE.

FREDERICK HACHMANN, OF ST. PAUL, MINNESOTA, ASSIGNOR OF THIRTY THIRTY-SECONDS TO FRANK L. GAZZOLO, JOHN R. PATTY, THOMAS L. BILLINGSLEY, STUART B. SHOTWELL, OTTO MULLER, AND CHARLES BRENCK, OF ST. PAUL, MINNESOTA.

SELF-OILING BEARING.

SPECIFICATION forming part of Letters Patent No. 766,244, dated August 2, 1904.

Application filed October 5, 1903. Serial No. 175,743. (No model.)

To all whom it may concern:

Be it known that I, FREDERICK HACHMANN, a citizen of the United States, residing at St. Paul, in the county of Ramsey and State of Minnesota, have invented certain new and useful Improvements in Self-Oiling Bearings; and I do hereby declare the following to be a full, clear, and exact description of the invention, such as will enable others skilled in the art to which it appertains to make and use the same.

My present invention relates to self-oiling bearings, and has for its especial object to provide an improved self-oiling bearing or journal for electric trolleys.

To the above ends the invention consists of the novel devices and combinations of devices hereinafter described, and defined in the claims.

20 The invention is illustrated in the accompanying drawings, wherein—

Figure 1 is a view in side elevation showing the head end of a trolley-pole and a trolley mounted thereon in accordance with my invention. Fig. 2 is a section on the line x^2x^2 of Fig. 1. Fig. 3 is a section on the line x^3x^3 of Fig. 2, some parts being broken away; and Fig. 4 is a detail in bottom plan view showing the recessed bearing-spindle.

30 Like characters indicate like parts throughout the several views.

The numeral 1 indicates the trolley-pole, to the free end of which is secured a pronged head 2. Large cap-nuts 3 fit seats formed in the sides or prongs of the head 2 with their sleeve portions projecting inward through the said prongs. The outer ends or heads of these cap-nuts 3 are rounded and are advisably knurled to enable the said cap-nuts to be turned 40 for a purpose which will presently appear.

A hollow bearing-spindle 4, having an enlarged cylindrical portion 5, is held in position by the two cap-nuts 3, which cap-nuts have screw-threaded engagements with the 45 ends of the same, as shown at 6, and normally close the said outer ends of the said spindle,

so that the cavity thereof will hold the lubricating-oil. The enlarged portion 5 of the said spindle is of the same diameter as the sleeve portions of the cap-nuts 3, and the said parts 50 closely abut, so as to form a continuous bearing for the trolley-sheave 7. The trolley-sheave 7 is provided with a removable bushing 8, which is secured thereto by a short screw-threaded engagement 9 and is held 55 against rotation with respect thereto by a key 10. The hub of this trolley is preferably of the same width as the enlarged portion 5 of the spindle 4, and hence is of less width than the distance between the sides or prongs of 60 the head 2, so that the said sheave is capable of a limited lateral movement with respect to the said head. The said sheave is yieldingly held in an intermediate position by a pair of retaining-springs 11, secured to the head 2, 65 and having annular extremities that engage the sides of the hub of said sheave.

After the cap-nuts 3 have been screwed into working positions on the ends of the spindle 4 they are held against rotation by keys 12, 70 driven into alined key-seats formed in said cap-nuts and in the prongs of the said head. As already stated, the heads of the said cap-nuts are rounded, and it should also be here noted that the prongs of the head 2 are beveled off, so that their upper portions incline downward and outward, as best shown in Fig. 2. In view of this construction if the trolley should jump the line-wire the line-wire cannot find lodgment either on the prongs of 80 the head 2 or on the heads of the cap-nuts 3, but, on the contrary, will be deflected out of line therewith.

In its lower portion the enlargement 5 of the spindle 4 is provided with a recess 13, 85 which extends nearly but not quite from end to end thereof and opens from the interior or cavity of said spindle to the peripheral portion of the said enlargement 5. This cavity or recess 13 contains a cylindrical plug or oil-distributer 14, formed of porous absorbent material, such as felt, and around the same is

wrapped a spiral spring 15, which holds the same in proper form and in proper position. The ends of the said spring 15 are preferably fitted into small seats or depressions 16, formed 5 in the end walls of the cavity 13, as best shown in Fig. 4. By reference to Fig. 3 it will be noted that the cavity 13 opens into the oil-containing cavity of the spindle 4 through a narrow slit 13^a, and it will also be noted that 10 the spring 15 holds the absorbent distributor 14 in an elevated position, so that it closes the said slit 13^a and is held slightly out of contact with the bearing-surface of the sheave-bushing 8. Hence it is evident that the oil contained 15 within the cavity of the spindle 4 can escape therefrom only by the combined action of capillary attraction and gravity, the former causing the absorbent distributor to be saturated with oil and the latter causing the oil to 20 drip slowly from the said distributor. Hence there will be no waste of oil; but the oil will be delivered to the journal in desired quantities. In some cases it may be found desirable to make the absorbent distributor 14 of such 25 diameter that it will have continuous contact with the bearing-surface of the bushing 8.

The journal is absolutely dust-proof, and when once the cavity of the spindle 4 is filled with oil it will keep the journal lubricated for 30 a very long time. When the bushing 8 becomes worn, it may be easily replaced by a new bushing, and when the bearing-surface of the spindle 4 becomes worn a new spindle may be easily substituted therefor, thus making 35 repairs possible at a very small cost.

It will of course be understood that the device described is capable of modification within the scope of my invention as herein set forth and claimed. It will also be understood

that the journal is capable of general use 40 wherever a self-oiling journal of this character may be found desirable.

What I claim, and desire to secure by Letters Patent of the United States, is as follows:

1. The combination with a bifurcated trolley-head 2, of the cap-nuts 3, seated in the prongs thereof and held against rotation, a hollow spindle 4 seated in said cap-nuts and having screw-threaded engagement therewith, said spindle having an oil-feeding passage and 45 an enlarged bearing portion 5, said bearing portion lying coincident with the sleeve portions of said cap-nuts, and a sheave mounted on said bearing portions 5 and adapted to move laterally onto the said sleeve portions of said 50 cap-nuts, substantially as described.

2. The combination with the trolley-head 2, having the cap-nuts 3, seated in the prongs thereof and held against rotation by keys 12, of the hollow spindle 4 held by said cap-nuts 60 and having screw-threaded engagement therewith, said spindle having the enlarged bearing portion 5 lying coincident with the sleeve portions of said cap-nuts, and further having a radial oil-feeding passage in its bearing portion 65 5, the sheave mounted to run on said bearing portions 5, and a body of absorbent material within said oil-passage, normally held close to but out of contact with the sleeve-engaging surface of said sheave, substantially 70 as described.

In testimony whereof I have affixed my signature in presence of two witnesses.

FREDERICK HACHMANN.

Witnesses:

E. H. KELIHER,
FRANK D. MERCHANT.
